JOHN CAHILL, OF NORFOLK, VIRGINIA

ROLLING PARTITION OR CLOSURE

Application filed June 18, 1923. Serial No. 646,193.

My invention relates to partitions, curtains, and like closures of the flexibly connected slat type, and particularly rolling closures or partitions.

The principal objects are to provide for mounting the roller so that it will automatically shift in response to the varying weight imposed upon it in the coiling and uncoiling of the slats; to provide for movement of the closure in a vertical plane and unencumbered or devoid of weight or friction other than of itself; to provide for utilizing the force of the lifting springs to automatically pull the closure towards or away from the wall opening to ensure the necessary space for the coils; to provide means effective as the tension on said springs is proportionately relieved to permit the roller mounting to swing away from the opening; to provide for compensating movement by means acting independently of the winding mechanism; to provide for compact rolling of the closure by means incorporated therein to compensate for expansion and contraction of the slats; to provide spaced roller sections adapted for heavy duty service; and to provide for storing spring power independently of the roller.

With such and other objects in view, the nature, characteristic features and scope of the invention will more readily be understood from the following description taken in connection with the accompanying drawings, forming a part hereof, wherein—

Figure 1 is a longitudinal sectional view of a roller and its supports.

Fig. 2 is an end view of the roller suspension mechanism.

Figs. 3 and 4 are modifications of the roller suspension mechanism.

Fig. 5 is a longitudinal sectional view of a modification showing the roller and its mounting, with the winding springs independent of the roller.

Fig. 6 is a transverse section of the structure, Fig. 5; and

Fig. 7 is a transverse section showing a preferred embodiment for compensating for expansion and contraction of the slats.

The numeral 5 represents the roller shaft

terminally supported by arms 6 the upper ends of which are pivotally attached to members 7. The latter may be independent brackets or they may constitute structural parts of the main housing or casing which may be in the opening in the building. In any event, they define the limits of the coil space. While the roller may be as usual it is a merit of the invention that it is embodied, as shown in Fig. 1, in sections 8 spaced apart, as at 9, and equipped with a lifting spring, as 10. The roller units may have an abutment or easer extension 11 to promote even winding of the curtain.

Intermediate the pivotal arms and the respective end roller sections are elements 12 fixedly secured to the roller shaft and represented in Figs. 1 and 2 in the form of segmental pulleys. They might, however, be of any other form calculated to perform the desired function which is to insure a yielding or compensating restraint on the roller mounting and permit the latter to adapt itself to varying diameters of coils on the roller in the raising and lowering of the flexibly joined slatted structure. For this purpose each of the elements 12 has secured to it, as at 13, one end of a strap or band 14, the other end of which is anchored, as at 15, to, for example, the bracket 7. When the shutter or closure is fully down, the springs which supply the lifting force are at their greatest tension. The effect of this is to cause the pivotal arms 6 to swing on their pivots towards the front of the coil space. This tendency is restrained by the straps 14 which are now taut. As the shutter rises, the tension on the lifting springs is proportionately relieved and the segmental pulleys are permitted to unwind a small portion of the straps 14 and thereby enable the arms 6 to retreat in order to provide the necessary space required for the additional coils of the shutter.

It is to be understood that the elements 12 are secured to the roller shaft, and that when the shutter is in lowered position the springs 10 are at a maximum tension. This insures that the elements 12 are held at their limit, as permitted by the straps 14, in an anticlock-

wise movement. This tends to swing the shaft-carrying ends of the arms 6 toward the front of the coil space, that is toward the right in Fig. 2. As the shutter is raised and coiled on the roller, the tension of the spring 10 is relieved and the weight of the shutter is added to the roller. As the tension of the spring is relieved the weight of the parts overcomes the spring and the element 12 is 5 permitted to turn in a clockwise direction, 10 unwinding the strap 14, and permitting the shutter roller to swing to the rear of the coil space, that is to the right in Fig. 2. The relations are balanced, and the movement 15 described is permitted in direct proportion to the winding up or raising of the shutter.

Figs. 3 and 4 show variable mountings for the roller which will enable it to shift in the coil space to compensate for large or small 20 coils. In Fig. 3, the roller carrying arms 16 are pivoted, as at 17, below and substantially in line with the roller shaft. They have angular offsets 18 which are forwardly directed and serve to carry one end of a coiled spring 25 19, the other end 20 being secured to the adjacent bracket. Manifestly, as thus arranged, the springs 19 exert their maximum pull when the partition is down. When the partition or shutter is about two-thirds up practically all tension is off the springs and their 30 relatively long terminal loops 21 are free to slide back and forth. In Fig. 4, the roller carrying arms 22 are pivoted, as at 23, in front of the center of gravity of the roller and have rearwardly directed extensions 24 to accommodate the coiled springs 25, the opposite ends of which are secured to the brackets. With the partition hung in this manner and the springs 25 at an angle to the horizontal, 40 the springs are always active and little effort relatively speaking is required to hold the partition to the groove.

Referring to Figs. 5 and 6, the coiling roller 26 is free of winding springs. To provide for this condition, I prefer to form the roller shaft carrying arms 27 with integral spring barrels 28. The shaft is journaled freely in the arms 27 and may be operated in any suitable way to wind the springs 29 50 which are secured, respectively, to it and to the barrels. The arms 27 are pivoted near the bottom of the coil space and by providing arcuate slots 30 in the ends thereof to accommodate the shaft, the roller mounting is afforded the necessary back and forth compensating movement to take care of different size coils.

Fig. 7 shows a simple expedient to compensate for expansion and contraction of the slats and to overcome any tendency to buckling. Adjoining slats 31 and 32 are provided with half housings 33 in confronting relation to admit of spring provisions 34. The 55 illustration indicates the permissible rela-

tive spreading of the slats to insure flush coiling.

The action of the forces concerning the operation of the pivot brackets 6 which cause the shaft and shutter to move in the arc of a circle to and from the wall while the shutter is closing and opening respectively may be better understood by a study of Fig. 2.

Let W_s = the weight of the uncoiled part of shutter.

r = the radius or distance from center of shaft to center line of shutter.

R = the radius or distance from the center of shaft to the center line of tension cable 14.

F = the restraining force acting through 14, exerted by the spring.

T = torque in spring.

Then equilibrium of forces around the shaft will exist when $W_s r = RF = T$.

It must be considered that as the shutter uncoils the weight W_s increases and increases the torque, therefore the moment RF can be no greater at any time than the moment $W_s ar$. Each is maximum when the shutter is closed as shown in Fig. 2, and minimum when the shutter is completely opened.

These forces would also exist if the shaft were mounted in stationary brackets, but in this invention the shaft is mounted in swinging brackets 6, and permits of further use of the forces of gravity and of the lifting or counterbalance spring.

In this case let
 W = the combined weight of shutter shaft and springs, always constant.

l = length of moment arm normal to W .

F = restraining force acting through 14.

L = moment arm normal to F , and maximum when the arm 6 approaches a vertical position.

Equilibrium in this case is expressed by $Wl = FL$.

The operation of the system is as follows: In its present position, Fig. 2, the shutter is closed completely and W_s is maximum, also the spring is charged to the maximum and the force F constrained by 14 is maximum. In this position the moment arm L is at its minimum length and the moment arm l is of maximum length.

As the shutter is opened (raised) the spring torque decreases and counterbalances the uncoiled part of the shutter. This decrease of torque consequently reduces the force F thereby reducing the moment FL . But the weight W has not changed, consequently the moment Wl would be greater than FL . This condition cannot exist as equilibrium of forces is upset, so the weight W acting downward causes the pivot brackets 6 to swing toward the vertical, thereby reducing the moment

arm l until the moment Wl is again equal to FL . But, the pivot brackets 6 cannot swing unless the sheave 12 turns to permit sufficient unwinding of 14. This unwinding may be considered as a simultaneous recharging of the spring effective to maintain the variable moments Wl and FL always equal and opposite. Since the moment FL is variable the moment Wl also will be variable because both always are equal. It is true that W , the weight, does not change and, therefore, in order that Wl can change to equal the variable FL , the lever arm l must change in length. The equation would be

15 Constant weight Wx variable l =variable Fx variable L .

It must be remembered that it is not the shutter rubbing against the wall as it coils which forces the lever arm 6 away from the 20 wall. It is the fact that the spring force has reduced, thereby reducing FL and consequently W drops down reducing l until $Wl=FL$. The opposite occurs when the shutter is uncoiled. Evidently, the forces act 25 practically instantaneously.

Having described my invention, I claim:

1. The combination of a coil space, a curtain operating roller therein, a shaft on which said roller is fixedly mounted, shaft 30 supports, and springs mounted in the shaft supports.

2. The combination of a coil space, a curtain operating roller therein, a shaft on which said roller is fixedly mounted, means 35 supporting the shaft whereby the roller is bodily movable with relation to the front of the coil space, and means controlled by the curtain-operating movement of the roller defining the extent of such movement.

40 3. The combination of a coil space, a curtain operating roller therein, a shaft on which said roller is fixedly mounted, shaft supports, including integral spring barrels, and springs secured relatively to the shaft 45 and barrels.

4. The combination of a curtain operating roller having shaft extensions, pivotal supports for the shaft extensions, and lifting springs carried by said supports and secured 50 thereto and to the shaft extensions.

5. The combination of a slatted closure, a roller on which said closure is coiled, a lifting spring for the roller for coiling the closure thereon, pivotal supports for the roller 55 to permit bodily movement thereof, said supports permitting bodily compensating movement of the roller under relieved tension of the lifting spring as the closure is coiled on the roller.

60 6. The combination of a slatted closure, a roller on which the closure is to be wound, a lifting spring for operating the roller to wind the closure thereon, and means for supporting the roller for bodily movement to 65 compensate for the coiling of the closure on

such roller, said means being held against roller compensating movement under full tension of the lifting spring and permitting roller compensating movement as the tension of the lifting spring is relieved.

7. The combination of a slatted closure, a roller on which the closure is to be coiled in raising the closure, a lifting spring for operating the roller in closure-raising movement, means whereby the roller is permitted a bodily movement to compensate for the wound closure, and means controlled by the tension of the lifting spring to permit bodily movement of the roller as the closure is wound thereon and the tension of the lifting spring is relieved.

In testimony whereof I affix my signature.

JOHN CAHILL.
